CLAIM

The ornamental design for a combined bookmark and felt-tipped marker, as shown and described.

DESCRIPTION

FIG. 1 is a right front perspective view of a combined bookmark and felt-tipped marker showing my new design in an exploded condition;

FIG. 2 is a front elevational view;

FIG. 3 is a right side elevational view;

FIG. 4 is a rear elevational view;

FIG. 5 is a left side elevational view;

FIG. 6 is an end elevational view taken from the right end of FIG. 2;

FIG. 7 is an end elevational view taken from the right end of FIG. 4; and

FIG. 8 is an elevational view taken in the direction of arrows 8—8 in FIG. 1.
